ATOMIZER

Edward A. Mikosz, Hamtramck, Mich.

Application February 13, 1939, Serial No. 256,192

1 Claim. (Cl. 299—88)

My invention relates to atomizers for liquids, such as perfume and the like, and has among its objects and advantages the provision of a simple and efficient atomizer of such proportions as to adapt it to be carried in the pocket, vanity case, purse and the like.

In the accompanying drawing:

Figure 1 is an elevational view of my invention; Figure 2 is a longitudinal sectional view; Figure 3 is a sectional view along the line 3—3 of Figure 1;

Figure 4 is an enlarged sectional detail view of the air and fluid conduits;

Figure 5 is an enlarged sectional view along the line 5—5 of Figure 2.

Figure 6 is a view similar to Figure 5 but illustrating the spray opening closed;

Figure 7 is a sectional view illustrating a liquid valve in its open position; and

Figure 8 is a view similar to Figure 7 illustrating the valve in its closed position.

In the embodiment selected to illustrate my invention, I make use of a tube 10 provided with screw thread formations 12 for the reception of a cap 14 provided with a seal 16 having pressure relation with the end of the tube. Inside the tube is a partition 18 which is located intermediate the ends of the tube in such manner as to provide a liquid containing chamber 20 and an air compressing chamber 22. Partition 18 has liquid-tight relation with the tube 10.

Inside the chamber 20 I position a tube 24 which has its lower end spaced slightly from the partition 18 for the inlet of liquid to be sprayed. Tube 24 may be welded to the tube 10 and has its upper end extending through a depressed wall area 2 in the tube 10 for bringing the upper end of the tube to a position exteriorly of the tube 10. Communicating with the tube 24 inside the tube 10 is a branch tube 28, which includes a right angular end 30 extending through the wall of the tube 10, as illustrated in Figure 5. To the outer face of the tube 10 I secure a semi-spherical shaped shell 32 having a spray opening 34. End 30 of the branch tube 28 communicates with the shell 32.

An air tube 36 has one end extending through the partition 18 and its other end extending upwardly of the tube 10 to a position slightly above the branch tube 28. This end of the tube 36 is closed by a plug 38. I connect a branch tube 40 with the tube 36, which branch tube includes right angular end 42 paralleling the end 30 and extending through the wall of the tube 10 immediately above the end 30. End 42 also has com-

munication with the shell 32. To the upper end of the tube 36 adjacent the side thereof I secure a short tube 44 which extends through the wall area depression 46 in the tube 10. Figures 1 and 5 illustrate a slide plate 46 guided for movement longitudinally of the tube 10 through the medium of guide flanges 48. The upper end of the slide plate 46 is fashioned with a head 50 adapted to be moved over the shell 32 for effectively sealing the spray opening 34. Slide plate 46 also carries a valve rod 52 slidable in the tube 24. A small tube 54 also has its upper end secured to the offset flange 56 of the slide plate and is slidably related to the tube 44. I provide the tube 54 with an air bleed 58, which air bleed is positioned slightly above the upper end of the tube 44 when the slide plate 46 is positioned according to Figures 1 and 5, at which time the chamber 20 is vented to the atmosphere.

When the slide plate 46 is moved downwardly of the tube 10 sufficiently far to bring the head 50 into sealing relation with the opening in the shell 32, vent opening 58 will be positioned inside the tube 40, and the latter tube fits tightly about the tube 54 so as to provide liquid-tight relation theretwixen.

Slide plate 46 is cut away at 58 to provide accommodation for the shell 32, and the head 50 is cut away at 60 to accommodate the shell 32 when the slide plate 46 is assembled with the tube 10. Valve tube 52 is provided with a plate 53 having an opening for slidably receiving a valve stem 55 connected with a valve 57 arranged to seat upon the valve seat 59 below the branch 28 to prevent liquid from flowing into the branch when the valve is closed. Between the valve 57 and the flange 53 I interpose a compression spring 61, and the upper end of the valve stem 55 is provided with an enlargement 63 which holds the valve stem 55 in assembled relation with the flange 53 when the valve is opened according to Figure 7. Figure 8 illustrates the valve in its closed position, at which time the spring 61 is flexed for firmly holding the valve against its seat.

In the chamber 22 I mount a piston 62 which includes a leather or other pliable sheet 64 clamped between plates 66 and 68, with the leather 64 of such diameter as to be foldable to provide a flange 70 fitting against the inner wall of the chamber 22. Plates 66 and 68 are held in clamping relation upon the leather 64 by a tubular rivet 72 which is fashioned at its inner end to provide a ball valve retainer 74, in addition to a valve seat 76. Flange 70 is held tightly against 55

the wall of the chamber 22 by a split spring element 78. Figure 2 illustrates a compression spring 80 interposed between the partition 18 and the piston 62 for urging the latter to the position of Figure 2.

A tubular actuating member 82 is slidably related to the tube 10, and one end of the member 82 is closed at 84. Member 82 slides inside the tube 10 defining the chamber 22 and has its inner 10 end bearing against the piston 62. I provide the member 82 with two longitudinal grooves 86, and the tube 10 may be depressed at 88 to provide lugs fitting inside the grooves 86 to prevent complete withdrawal of the member 82. However, the member 82 may be pressed inwardly of the chamber 22 against the tension of the spring 80, and the member will be returned quickly to the position of Figure 2 when pressure is released from the member. Air vents 90 are provided in the member 82.

Member 82 may be provided with laterally extending grooves 92 communicating with the grooves 86 for the reception of the depressed lugs 88 when the member 82 is shoved completely 25 home and rotated about its longitudinal axis relatively to the tube 10. Thus the member 82 may be supported substantially housed inside the chamber 22 against the tension of the spring 80.

30 In operation, liquid in the chamber 20 is atomized through reciprocation of the member 62, which causes air to pass through the tube 36 and liquid from the chamber 20 to pass through the tube 24. Such air and liquid are admixed in 35 the shell 32 and ejected therefrom in an atomized condition through the orifice 34. The unit is of small proportions so as to facilitate carrying

on the person, as in the pocket, purse or the like. Chamber 20 is easily filled by merely removing the cap 14. Member 82 includes a knurled flange 94 which facilitates manipulation, particularly when rotating the member to bring the lugs 88 into locking relation with the grooves 92. Slide plate 46 is provided with a spring 96 having a bulge 98 arranged to have pressure relation with a rib 100 formed on the outer face of the tube 10 so as to yieldingly hold the head 50 in pressure relation 10 with the shell 32 so as to prevent accidental shifting of the slide plate. The slide plate is humped at 102 to provide accommodation for the spring 96.

I claim:

15 In an atomizer of the type described, a tubular member provided with a partition dividing the member into a liquid chamber and an air compression chamber, a cap for closing the liquid chamber, the latter being provided with a nozzle, 20 an air tube having an end communicating with the nozzle and its other end communicating with the air compression chamber, a liquid conveying tube communicating with the liquid chamber and said nozzle, a piston operable in the air compression chamber for compressing air into the air tube and through the nozzle, manually actuated means for operating said piston, a nozzle closing means movably related to the tubular member, valve means associated with the liquid conveying 25 tube, an air venting valve associated with the liquid chamber, and operating connections between the nozzle closing means and the valve means and the air venting valve for closing the same when the nozzle is closed and vice versa. 30 35

EDWARD A. MIKOSZ.
